ABSTRACT OF THE DISCLOSURE

Compounds of the type substituted 4-amino-nicotinic acids, nicotinates, nicotinamides and salts are described. The compounds are useful for their diuretic and anti-inflammatory activity.

This invention is a continuation-in-part of our application Ser. No. 459,893, filed May 28, 1965, and now abandoned.

This invention relates to new organic compounds. More particularly, it relates to derivatives of nicotinic acid, compositions containing said derivatives and methods of administering said compositions.

The novel compounds of the present invention can be represented as compounds of the formula:

wherein R₁ is selected from the group consisting of (lower alkyl)-phenyl, xylol, nitrophenyl, halophenyl, hydroxyphenyl, carboxyphenyl, aminophenyl, α,α,α -trifluorotolyl, halo- α,α,α -trifluorotolyl and dihalotolyl; R₂ is selected from the group consisting of hydroxy, lower alkoxy, di-lower alkylamino lower alkoxy, amino, lower alkylamino and di-lower alkylamino and pharmaceutically acceptable salts thereof.

The compounds of this invention form water-soluble acid addition salts. Since these compounds are valuable therapeutic agents, medicinally acceptable acid addition salts formed from pharmaceutically acceptable acids are preferred. These addition salts may be formed with both organic and inorganic acids such as hydrochloric acid, nitric acid, citric acid, maleic acid, fumaric acid, cussinic acid, sulfuric acid, phosphoric acid, tartaric acid and the like.

The nicotinic acid derivatives of this invention form alkaline metal salts such as the sodium and potassium the aluminum or magnesium salts or salts of alkaline earth metals, examples of which are barium and calcium.

The nicotinic acid esters of this invention react with

2

unsymmetrically disubstituted hydrazines to furnish nicotinic acid salts of the formula:

wherein R₁ is as defined hereinbefore, and R₃, R₄ and R₅ are selected from the group consisting of lower alkyl and aryl and R₃ and R₄ taken together with nitrogen are selected from the group consisting of pyrrolidino, piperidino, morpholino, 4-lower alkyl piperazino, 4-(β -hydroxyloweralkyl)piperazino, and hydroxypiperidino. These salts are also to be considered within the scope of the present invention.

20 The free bases of compounds of this invention are, in general, crystalline solids, at least somewhat soluble in the usual organic solvents and water.

The compounds of this invention are physiologically active and therefore useful in the pharmaceutical field. We have found that they are particularly advantageous as anti-inflammatory agents and diuretics in warm-blooded animals.

These compounds were shown to possess anti-inflammatory activity by a test that involves reduction of the edema caused by the injection of a 1% carageenin solution into the paws of rats.

These compounds were also shown to produce diuresis in both rats and dogs. Diuretic property in mature rats, for example, was determined by the following procedure:

35 Four cages (2 rats per cage) of mature male rats weighing between 180 and 300 grams were allowed a normal fluid intake prior to testing. The single oral administration of 400 micrograms of the test compound was given in 0.5 milliliter of 2 percent aqueous starch suspension. Four 40 cages (2 rats per cage) served as controls. Control animals received only the starch suspension. After administration, the test animals were placed in metabolism cages. Observations of the amount of urine excreted were made after 5 hours. These urine measurements were then adjusted 45 to compensate for differing weights of individual animals. The 5 hour urine samples of both control and treated rats were assayed for sodium and chloride content.

An illustrative group of compounds within the scope of the present invention include for example, 4-(α,α,α -trifluoro-m-toluidino)nicotinic acid; 4-(2,3-xylidino)nicotinic acid; 4-(2,6-dichloro-m-toluidino)nicotinic acid; 4-(2,6-dichloroanilino)nicotinic acid; 4-(o-toluidino)nicotinic acid; 4-(m-toluidino)nicotinic acid; 4-(p-toluidino)nicotinic acid; 4-(m-chloroanilino)nicotinic acid; 4-(m-fluoroanilino)nicotinic acid; methyl 4-(α,α,α -trifluoro-m-toluidino)nicotinate; dimethylaminoethyl 4-(α,α,α -trifluoro-m-toluidino)nicotinate; 4-(α,α,α -trifluoro-m-toluidino)nicotinamide, and the like.

50 The following Flowsheet A shows a specific illustration of the preparation of a specific final product of this invention.

In the above Flowsheet A, 4-nitronicotinic acid 1-oxide (I) is heated with α,α,α -trifluoro-m-toluidine (II) to give 25 4-(α,α,α -trifluoro-m-toluidino)nicotinic acid 1-oxide (III) which on hydrogenation over palladium-on-carbon gives 4-(α,α,α -trifluoro-m-toluidino)nicotinic acid (IV).

Alternatively, 4-(α,α,α -trifluoro-m-toluidino)nicotinic acid 1-oxide (III) may be prepared by heating 4-chloronicotinic acid 1-oxide (V) with (II). Also, 4-(α,α,α -trifluoro-m-toluidino)nicotinic acid (IV) may be prepared by heat 4-chloronicotinic acid (VI) with (II).

An alternative method of preparing the compounds of this invention is shown by the following example. 4-aminonicotinic acid (VII) is heated with 3-bromo- α,α,α -trifluorotoluene (VIII) in the presence of copper-copper

nicotinate (IX) is prepared by treatment of 4-(α,α,α -trifluoro-m-toluidino)nicotinic acid (IV) with methanol and sulfuric acid. Treatment of (IX) with ammonia affords 4-(α,α,α -trifluoro-m-toluidino)nicotinamide (XI). Treatment of (IX) with dimethylamine in a suitable solvent or sodium methoxide in dimethylformamide gives N,N-dimethyl 4-(α,α,α -trifluoro-m-toluidino)nicotinamide (XII). N-methyl-4-(α,α,α -trifluoro-m-toluidino)nicotinamide is prepared by treatment of (IX) with sodium methoxide in methylformamide. Treatment of sodium 4-(α,α,α -trifluoro-m-toluidino)nicotinate (XIII) with β -dimethylaminoethylchloride affords dimethylaminoethyl 4-(α,α,α -trifluoro-m-toluidino)nicotinate (XIV).

oxide and potassium carbonate to give 4-(α,α,α -trifluoro-m-toluidino)nicotinic acid (IV):

Treatment of methyl 4(α,α,α -trifluoro-m-toluidino)nicotinate (IX) with unsym-dimethylhydrazine using an excess of the hydrazine as solvent, or in the presence of an inert solvent, produces the hydrazinium salt (X).

The above described 4-aryl nicotinic acid may be transformed to related derivatives (Flowsheet B). For example, the ester, methyl 4-(α,α,α -trifluoro-m-toluidino)

Similarly, by the above described procedure, the reaction of the various 4-substituted nicotinic esters in list A 75 with the unsymmetrically substituted hydrazines in list

B produces the desired hydrazinium derivatives indicated in list C as follows:

suitable oral unit dosage forms in accord with this invention are tablets, capsules, pills, powder, packets,

A	B	C
Methyl 4-(α,α,α -trifluoro-m-toluidino)-nicotinate.	unsym-Diphenylhydrazine.....	1-methyl-1,1-diphenylhydrazinium 4-(α,α,α -trifluoro-m-toluidino)nicotinate.
Do.....	1-methyl-1-phenylhydrazine.....	1,1-dimethyl-1-phenylhydrazinium 4-(α,α,α -trifluoro-m-toluidino)nicotinate.
Butyl 4-(α,α,α -trifluoro-m-toluidino)-nicotinate.	1-aminopyrrolidine.....	1-amino-1-butylpyrrolidinium 4-(α,α,α -trifluoro-m-toluidino)nicotinate.
Methyl 4-(α,α,α -trifluoro-m-toluidino)-nicotinate.	1-aminopiperidine.....	1-amino-1-methylpiperidinium 4-(α,α,α -trifluoro-m-toluidino)nicotinate.
Methyl 4-(p-chloro- α,α,α -trifluoro-m-toluidino)nicotinate.	1-aminomorpholine.....	1-amino-1-methylmorpholinium 4-(p-chloro- α,α,α -trifluoro-m-toluidino)nicotinate.
Methyl 4-(α,α,α -trifluoro-m-toluidino)-nicotinate.	1-amino-4-methylpiperazine.....	1-amino-1,4-dimethylpiperazinium 4-(α,α,α -trifluoro-m-toluidino)nicotinate.
Do.....	1-amino-3-hydroxypiperidine.....	1-amino-3-hydroxy-1-methylpiperidinium 4-(α,α,α -trifluoro-m-toluidino)nicotinate.
Do.....	1-amino-4-(β -hydroxyethyl)-piperazine.....	1-amino-4-(β -hydroxyethyl)-1-methylpiperizinium 4-(α,α,α -trifluoro-m-toluidino)-nicotinate.

The compounds of the present invention may be administered as active components of compositions for administration in unit dosage form as tablets, pills, capsules, powders, granules, sterile parenteral solutions or suspensions, oral solutions or suspensions and the like. The dosage found effective may vary from 1 mg. to 200 mg. per kilogram depending upon the warm-blooded animal. For preparing solid compositions such as tablets, the principal active ingredient is mixed with conventional tableting ingredients such as corn starch, lactose, sucrose, sorbitol, talc, stearic acid, magnesium stearate, dicalcium phosphate, gums, and functionally similar materials as pharmaceutical diluents or carriers. The tablets or pills of the novel compositions can be laminated or otherwise compounded to provide a dosage form affording the advantage of prolonged or delayed action or predetermined successive action of the enclosed medication. For example, the tablet or pill can comprise an inner dosage and an outer dosage component, the latter being the form of an envelope over the former. The two components can be separated by an enteric layer which serves to resist disintegration in the stomach and permits the inner component to pass intact into the duodenum or to be delayed in release. A variety of materials can be used for such enteric layers or coatings, such materials including a number of polymeric acids or mixtures of polymeric acids with such materials as shellac, shellac and cetyl alcohol, cellulose acetate, and the like. A particularly advantageous enteric coating comprises a styrene maleic acid copolymer together with known materials contributing to the enteric properties of the coating.

The liquid forms in which the novel composition of the present invention may be incorporated for administration include aqueous solutions, suitable flavored syrups, aqueous or oil suspensions, flavored emulsions with edible oils such as cottonseed oil, sesame oil, coconut oil, peanut oil, and the like, as well as elixirs and similar pharmaceutical vehicles. Suitable dispersing or suspending agents for aqueous suspensions include synthetic and natural gums such as tragacanth, acacia, alginate, dextran, sodium carboxymethylcellulose, methylcellulose, polyvinylpyrrolidone, gelatin and the like. Sterile suspensions or solutions are required for parenteral use. Isotonic preparations containing suitable preservatives are also highly desirable for injection use.

The term unit dosage form as used in the specification and claims, refers to physically discrete units suitable as unitary dosages, each unit containing a predetermined quantity of active material calculated to produce the desired therapeutic effect in association with the required pharmaceutical diluent, carrier or vehicle. The specifications for the novel unit dosage forms of this invention are dictated by and are directly dependent on (a) the unique characteristic of the active material and the particular therapeutic effect to be achieved, and (b) the limitations inherent in the art of compounding such an active material for therapeutic use in warm-blooded animals, as disclosed in detail in this specification, these being features of the present invention. Examples of

granules, wafers, cachets, teaspoonsfuls, dropperfuls, ampules, vials, segregated multiples of any of the foregoing and other forms as herein described.

The following examples describe in detail the preparation of intermediates and nicotinic acid derivatives final products of the present invention.

Example 1.—Preparation of 4-(α,α,α -trifluoro-m-toluidino)-nicotinic acid 1-oxide

(A) A mixture of 3.0 g. of 3-nitronicotinic acid 1-oxide and 12 ml. of α,α,α -trifluoro-m-toluidine is heated at 140°-150° C. for 3 hours. Upon cooling, the mixture is dissolved in 10% aqueous potassium hydroxide and washed with ether. The aqueous layer is acidified to give 4.1 g. of 4-(α,α,α -trifluoro-m-toluidino)-nicotinic acid 1-oxide as a tan powder, melting point 277°-280° C. dec.

(B) A mixture of 1.0 g. of 4-chloronicotinic acid 1-oxide and 3 ml. of α,α,α -trifluoro-m-toluidine is heated at 130° C. for 1.5 hours, cooled and filtered, to give 2.0 g. of white crystals. The solid is stirred into 70 ml. of warm water, cooled and filtered to give 1.2 g. of 4-(α,α,α -trifluoro-m-toluidino)-nicotinic acid 1-oxide as a tan powder, melting point 282° C. dec.

Example 2.—Preparation of 4-(α,α,α -trifluoro-m-toluidino)-nicotinic acid

(A) A suspension of 4.0 g. of 4-(α,α,α -trifluoro-m-toluidino)-nicotinic acid 1-oxide and 800 mg. of 10% palladium-on-carbon catalyst is hydrogenated at 60° and 45 lb. pressure for 2.5 hours. The catalyst is filtered and washed with ethanol. The combined filtrates are evaporated to a pink crystalline mass, melting point 258°-260° C. dec. which is crystallized from ethanol to give 2.0 g. of 4-(α,α,α -trifluoro-m-toluidino)-nicotinic acid as colorless crystals, melting point 260°-262° C., dec. A sample is prepared for analysis by sublimation at 180° C. and 0.01 mm. Hg to give melting point 265°-267° C.

(B) A mixture of 1.0 g. of 4-aminonicotinic acid, 1.0 g. of potassium carbonate, 5 mg. of cupric oxide, 5 mg. of copper powder, 18 g. of 3-bromo- α,α,α -trifluorotoluene and 5 ml. of n-hexanol is heated at reflux in an inert atmosphere for 70 hours, cooled, diluted with ether and filtered. The resulting brown paste is dissolved in 10% potassium hydroxide solution, filtered, is neutralized with 6 N hydrochloric acid. Filtration gives 160 mg. of brown powder which, after crystallization from methanol, gives 70 mg. of 4-(α,α,α -trifluoro-m-toluidino)-nicotinic acid, melting point 264°-266° C. Infrared spectral analysis shows this product to be identical with the authentic sample described in paragraph A above.

(C) A mixture of 200 mg. of 4-chloronicotinic acid and 1.4 ml. of α,α,α -trifluoro-m-toluidine is heated at 150° C. for 1 hour and at 200° C. for 1 hour. Upon cooling, 40 ml. of water is added and the mixture is distilled until all α,α,α -trifluoro-m-toluidine is removed. Crystallization occurs in the still during distillation. Filtration gives 265 mg. of 4-(α,α,α -trifluoro-m-toluidino)-nicotinic acid, melting point 262° C. dec. The compound of this example is particularly useful as a diuretic.

Example 3.—Preparation of 4-(2,3-xylidino)-nicotinic acid

A mixture of 3.0 g. of 4-nitronicotinic acid 1-oxide and 12 ml. of 2,3-dimethylaniline is heated at 150° C.

Examples 6-18

In the manner described in Example 2, part C, treatment of 4-chloronicotinic acid with the appropriate amine gives the products of Table I.

TABLE I

Example No.	Starting Amine	Product	Melting point, ° C.
6	α,α,α -Trifluoro-p-toluidine	4-(α,α,α -trifluoro-p-toluidino)nicotinic acid	269-271
7	<i>o</i> -Chloroaniline	4-(<i>o</i> -chloroanilino)nicotinic acid	286-288
8	<i>p</i> -Chloroaniline	4-(<i>p</i> -chloroanilino)nicotinic acid	277-279
9	3,4-xylidine	4-(3,4-xylidino)nicotinic acid	269-271
10	3,5-xylidine	4-(3,5-xylidino)nicotinic acid	294-296
11	<i>m</i> -Ethylaniline	4-(<i>m</i> -ethylanilino)nicotinic acid	248-250
12	<i>o</i> -Aminobenzoic acid	4-(<i>o</i> -carboxyanilino)nicotinic acid	324-326
13	<i>m</i> -Aminobenzoic acid	4-(<i>m</i> -carboxyanilino)nicotinic acid	302-304
14	<i>m</i> -Fluoroaniline	4-(<i>m</i> -fluoroanilino)nicotinic acid	295-297
15	<i>m</i> -Aminophenol	4-(<i>m</i> -hydroxyanilino)nicotinic acid	318-320
16	5-amino-2-chlorobenzotrifluoride	4-(<i>p</i> -chloro- α,α,α -trifluoro- <i>m</i> -toluidino)nicotinic acid	266-269
17	<i>m</i> -Nitroaniline	4-(<i>m</i> -nitroanilino)nicotinic acid	288-290
18	2,6-dichloro- <i>m</i> -toluidine	4-(2,6-dichloro- <i>m</i> -toluidino)nicotinic acid	310-312

for 4 hours, cooled and poured into 10% aqueous potassium hydroxide. After extraction with ether, the aqueous layer is filtered and neutralized to give 2.5 g. of 4-(2,3-xylidino)-nicotinic acid 1-oxide as a tan powder, melting point 262°-265° C. dec.

The above oxide is suspended in 150 ml. of acetic acid containing 800 mg. of 10% palladium-on-carbon catalyst and is hydrogenated at 60° and 45 lb. pressure for 8 hours. The catalyst is filtered and the filtrate is concentrated to give, upon addition of ethanol, 1.3 g. of 4-(2,3-xylidino)-nicotinic acid, melting point 295°-300° C. dec. A sample for analysis is prepared by sublimation at 200° C. and 0.01 mm. Hg to give colorless crystals, melting point 296°-300° C. dec. This compound is particularly useful as an anti-inflammatory agent.

Example 4.—Preparation of 4-(*m*-chloroanilino)-nicotinic acid

A mixture of 4.0 g. of 4-nitronicotinic acid 1-oxide and 15 ml. of *m*-chloroaniline is heated at 160° C. for 2 hours. Upon cooling, a 10% potassium hydroxide solution is added and the resulting solution is washed several times with ether. The ether extracts are discarded and the aqueous layer is neutralized with 6 N hydrochloric acid to give 4.4 g. of 4-(*m*-chloroanilino)nicotinic acid 1-oxide, melting point 288°-290° C.

A 750 mg. portion of 4-(*m*-chloroanilino)-nicotinic acid 1-oxide in 150 ml. of acetic acid containing 500 mg. of 10% palladium-on-carbon is hydrogenated at 60° C. and 35 lb. pressure for 24 hours. Filtration of the catalyst and evaporation of the filtrate gives 700 mg. of tan solid which upon suspension in acetone and filtration gives 450 mg. of 4-(*m*-chloroanilino)-nicotinic acid, melting point 250° C. dec. Crystallization from water gives colorless needles, melting point 285°-289° C. dec.

Example 5.—Preparation of 4-(*m*-toluidino)-nicotinic acid

A mixture of 3 g. of 4-nitronicotinic acid 1-oxide and 10 ml. of *m*-toluidine is heated at 100° C. from 1 hour and at 140° C. for 4 hours. Upon cooling, a 10% aqueous potassium hydroxide solution is added and the resulting solution is washed several times with ether. The ether extracts are discarded and the aqueous layer is filtered and neutralized with 6 N hydrochloric acid to give 3.1 g. of 4-(*m*-toluidino)-nicotinic acid 1-oxide, melting point 270°-272° C.

A suspension of 2.5 g. of the above 4-(*m*-toluidino)-nicotinic acid 1-oxide in 200 ml. of acetic acid containing 800 mg. of 10% palladium-on-carbon is hydrogenated at 60° C. and 45 lb. pressure for 24 hours. If incomplete reduction is observed, the reaction may be repeated using methanol as solvent. Filtration of the catalyst and concentration of the methanol gives 4-(*m*-toluidino)-nicotinic acid, melting point 276°-278° C.

Example 19.—Preparation of sodium 4-(α,α,α -trifluoro-*m*-toluidino)-nicotinate

A solution of 1.41 g. of 4-(α,α,α -trifluoro-*m*-toluidino)-nicotinic acid in 50 ml. of 0.10 N sodium hydroxide is evaporated to a creamy white paste which is dissolved in ethanol, filtered and concentrated until crystallization occurs. Filtration gives 400 mg. of sodium 4-(α,α,α -trifluoro-*m*-toluidino)-nicotinate as a white, water soluble powder which has high diuretic activity.

Example 20.—Preparation of N-(2-dimethylaminoethyl)-4-(α,α,α -trifluoro-*m*-toluidino)-nicotinate

A mixture of 2.74 g. of sodium 4-(α,α,α -trifluoro-*m*-toluidino)-nicotinate and 1.05 g. of 2-chloro-N,N-dimethylethylaniline in 30 ml. of ethanol is stirred for 24 hours at room temperature. The mixture is filtered and the filtrate is concentrated under reduced pressure. Crystallization from methanol-petroleum ether gives N-(2-dimethylaminoethyl)-4-(α,α,α -trifluoro-*m*-toluidino)-nicotinate.

Example 21.—Preparation of methyl-4-(α,α,α -trifluoro-*m*-toluidino)-nicotinate

A mixture of 3.25 g. of sodium 4-(α,α,α -trifluoro-*m*-toluidino)-nicotinate and 10 ml. of methyl iodide in 100 ml. of ethanol is stirred at room temperature for 16 hours. The mixture is filtered and the filtrate is concentrated under reduced pressure to give methyl 4-(α,α,α -trifluoro-*m*-toluidino)-nicotinate, melting point 118-121° C. after purification by sublimation.

Example 22.—Preparation of 4-(α,α,α -trifluoro-*m*-toluidino)-nicotinamide

A solution of 1.47 g. of methyl 4-(α,α,α -trifluoro-*m*-toluidino)-nicotinate and 20 ml. of ammonia in 80 ml. of ethanol is heated in steel autoclave at 50° C. for 8 hours. The residue which is obtained in concentration of the mixture of dryness under reduced pressure is crystallized from ethanol and water to give 4-(α,α,α -trifluoro-*m*-toluidino)-nicotinamide, melting point 237-239° C. The above compound has analgesic activity.

Example 23.—Preparation of N,N-dimethyl-4-(α,α,α -trifluoro-*m*-toluidino)-nicotinamide

A solution of 1.33 g. of methyl 4-(α,α,α -trifluoro-*m*-toluidino)-nicotinate and 14 ml. of dimethylaniline in 80 ml. of ethanol is heated in a steel autoclave at 50° C. for 8 hours. The residue obtained on concentration of the mixture to dryness is crystallized from methanol and water to give N,N-dimethyl-4-(α,α,α -trifluoro-*m*-toluidino)-nicotinamide.

Example 24.—Preparation of n-methyl-4-(α,α,α -trifluoro-*m*-toluidino)-nicotinamide

A solution of 300 g. of methyl 4-(α,α,α -trifluoro-*m*-toluidino)-nicotinate and 14 ml. of dimethylaniline in 80 ml. of ethanol is heated in a steel autoclave at 50° C. for 8 hours. The residue obtained on concentration of the mixture to dryness is crystallized from methanol and water to give N,N-dimethyl-4-(α,α,α -trifluoro-*m*-toluidino)-nicotinamide.

toluidino)-nicotinate and 300 mg. of sodium methoxide and 1 ml. of methylformamide is heated at 95° C. for 18 hours. After cooling and diluting with water, the reaction mixture is extracted with ether, and the ether solution washed with water dried and evaporated to give 300 mg. of off-white crystals, melting point 140–144° C. The product is crystallized from acetone-hexane to give N-methyl-4-(α,α,α -trifluoro-m-toluidino)-nicotinamide as white crystals, melting point 144–146° C.

Example 25.—Preparation of butyl 4-(α,α,α -trifluoro-m-toluidino)-nicotinate 10

A solution of 3.0 g. of 4-(α,α,α -trifluoro-m-toluidino)-nicotinic acid in 20 ml. of n-butyl alcohol and 4 ml. of H₂SO₄ is heated at reflux for 16 hours, cooled and neutralized with NH₄OH. The product is extracted into chloroform, and the extract is washed with 10% NaOH and with water. After evaporation, the resulting oil is chromatographed on 150 g. of silica gel. Ether-dichloromethane (3:7) gives, upon evaporation, 1.5 g. of colorless crystals (7), melting point 48–52°. The ether is recrystallized from etherhexane, cooled to –60° to give butyl 4-(α,α,α -trifluoro-m-toluidino)-nicotinate as crystals, melting point 44–46° C.

Example 26.—4-(m-fluoroanilino)-nicotinic acid

A mixture of 4.0 g. of 4-nitronicotinic acid 1-oxide and 12 ml. of m-fluoroaniline is heated at 200° for 4 hours, cooled and dissolved in 10% aqueous sodium hydroxide. After extraction with ether, the aqueous layer is filtered and acidified. The resulting product 3.0 g. of 4-(m-fluoroanilino)-nicotinic acid 1-oxide is hydrogenated at 60° and 35 lb. pressure for 18 hours in 200 ml. of acetic acid containing 1.0 g. of 10% palladium-on-carbon. The catalyst is filtered and the filtrate is evaporated. Addition of methanol gives 4-(m-fluoroanilino)-nicotinic acid as white needles, melting point 292°–294° C. A sample for analysis may be prepared by sublimation.

Example 27.—Preparation of 4-(m-aminoanilino)-nicotinic acid

A mixture of 1.0 g. of 4-(m-nitroanilino)-nicotinic acid in 60 ml. of acetic acid containing 250 mg. of 10% palladium-on-carbon catalyst is hydrogenated at 60° and 25 lb. pressure for 1 hour. After cooling and filtering, the solvent is evaporated. The addition of methanol gives, after filtration, 570 mg. of white plates, melting point 291–292° C. Several crystallizations from methanol gives 4-(m-aminoanilino)-nicotinic acid as crystals, melting point 298–299° C.

Example 28.—Preparation of 4-(α,α,α -trifluoro-m-toluidino)-nicotinic acid hydrochloride

A solution of 1.0 g. of 4-(α,α,α -trifluoro-m-toluidino)-nicotinic acid in 100 ml. of methanol is saturated with a stream of hydrogen chloride gas. The solution is evapo-

rated and the residue is filtered from dichloromethane to give 1.1 g. of 4-(α,α,α -trifluoro-m-toluidino)-nicotinic acid hydrochloride as a white powder, melting point 278–282° C.

5 Example 29.—Preparation of 1,1,1-trimethylhydrazinium 4-(α,α,α -trifluoro-m-toluidino)-nicotinate

A solution of 2.2 g. of methyl 4-(α,α,α -trifluoro-m-toluidino)-nicotinate in 15 ml. of unsymmetrical dimethylhydrazine is heated at reflux overnight. After evaporation of the solvent, the residue is crystallized from dichloromethane-ether to give 2.3 g. of 1,1,1-trimethylhydrazinium 4-(α,α,α -trifluoro-m-toluidino)-nicotinate as white needles, melting point 118–121° C.

We claim:

1. A 4-amino-nicotinoyl compound selected from the group consisting of a compound of the formula:

20 wherein R₁ is selected from the group consisting of (lower alkyl)phenyl, halophenyl, α,α,α -trifluorotolyl, and halo- α,α,α -trifluorotolyl; R₂ is selected from the group consisting of hydroxy, lower alkoxy and amino, and pharmaceutically acceptable salts.

25 2. The 4-amino-nicotinoyl compound according to claim 1: 4-(α,α,α -trifluoro-p-toluidino)-nicotinic acid.

30 3. The 4-amino-nicotinoyl compound according to claim 1: methyl 4-(α,α,α -trifluoro-m-toluidino)-nicotinate.

35 4. The 4-aminonicotinoyl compound according to claim 1: 4-(m-chloroanilino)-nicotinic acid.

5. The 4-amino-nicotinoyl compound according to claim 1: 4-(o-chloroanilino)-nicotinic acid.

6. The 4-amino-nicotinoyl compound according to claim 1: sodium 4-(α,α,α -trifluoro-m-toluidino)-nicotinate.

7. The 4-amino-nicotinoyl compound according to claim 1: 4-(α,α,α -trifluoro-m-toluidino)-nicotinic acid.

8. The 4-amino-nicotinoyl compound according to claim 1: 4-(α,α,α -trifluoro-p-chloro-m-toluidino)-nicotinic acid.

9. The 4-amino-nicotinoyl compound according to claim 1: 4-(o-toluidino)-nicotinic acid.
